[57] CLAIM

The ornamental design for a combined salt shaker and pepper mill, as shown and described.

DESCRIPTION

FIG. 1 is a perspective view of a combined salt shaker and pepper mill showing our new design;

FIG. 2 is a side elevational view thereof;

FIG. 3 is a top plan view thereof;

FIG. 4 is a bottom plan view thereof;

FIG. 5 is a side elevational view thereof, rotated 36 degrees with respect to the view depicted in FIG. 2; and,

FIG. 6 is a side elevational view thereof, from the same direction as the view depicted in FIG. 5, showing the combined salt shaker and pepper mill in use with peppercorns contained therein, the peppercorns being shown for illustrative purposes only and forming no part of the claimed design.

FIG. 1

FIG. 2
